FIG. 1

FIG. 2

RULER DEVICE FOR DECIMAL-OCTAL CONVERSION

BACKGROUND OF THE INVENTION

This invention relates to a device for decimal to octal conversion of integers and vice versa and, more particularly, the invention is concerned with providing a relatively simple and accurate means for converting a decimal number to its octal equivalent by the use of a ruler device wherein the conversion is obtained directly therefrom.

In working with computers it is very often necessary to convert decimal numbers into their octal equivalents. The procedure presently in use to accomplish this conversion is described in several printed publications, for instance, McGraw-Hill Encyclopedia of Science and Technology, Vol. 9, pages 223. As can be seen from this publication and the following example, the conversion process becomes very tedious for high digit numbers and, consequently, subject to errors and mis-calculations.

To find the octal equivalent of the decimal number 88,012 in the manner presently in use, the number denoted as $88,012_{10}$ is essentially divided by 8. However, unlike the regular division system where one is interested in the integer quotient and the final remainder, in the decimal to octal conversion one is primarily interested in the series of remainders obtained in the necessary steps of the division procedure. These remainders arranged successively from right to left represent the octal equivalent in juxtaposition. In each division step the remainder is in the range of the integers from 0 to 7. The remainder in the first division step is the least significant digit of the octal number, the one in the second step is the next digit in the octal number in the direction to the left, and so forth until the division process is completed.

It would be most desirable to provide a device wherein the conversion of the decimal to octal conversion or vice versa could be easily accomplished without the requirement of tedious division steps wherein errors in calculation might be expected to occur.

SUMMARY OF THE INVENTION

The present invention is concerned with providing a device to ease the process of decimal to octal conversion and vice versa. The device includes a flat disc or ground plate upon which are imprinted a series of related scales arranged in circles around its center and a radially disposed indicator arm pivotable around the center of the disc. The main scale is a 360° circle divided into 100 parts and a concentric inner scale includes figures which are related by a factor of 8 with the main scale. Outside the main scale is a periodic 7 scale and outside this scale is another periodic 7 scale that is shifted in phase by 4.

Accordingly, it is an object of the invention to provide a means for converting a number expressed in the decimal system to its corresponding octal system equivalent and vice versa.

Another object of the invention is to provide a device which will eliminate the need for tedious arithmetical calculations normally required for decimal to octal conversion in computer work.

Still another object of the invention is to provide an efficient decimal-octal conversion device which is sim-

ple to use by relatively untrained personnel and which requires only a minimum of simple movements to accurately make the necessary conversion.

A further object of the invention is to provide a device which is simple and easy to construct in quantity for general use in computer work and which reduces the chance of error while at the same time permits more rapid and accurate determination of the necessary information.

These and other objects, features, and advantages will become more apparent after considering the following detailed description taken in conjunction with the annexed drawings and appended claims.

BRIEF DESCRIPTION OF THE DRAWINGS

FIG. 1 is a top plan view of the ruler device according to the invention showing the relative positions of the various scales and the radially disposed pivotably mounted indicator arm; and

FIG. 2 is a sectional view taken along the line 2-2 of FIG. 1.

DESCRIPTION OF A PREFERRED EMBODIMENT

Referring now to the drawings, there is shown a preferred embodiment of the ruler device for decimal-octal conversion according to the invention. The device includes a flat disc 13 constructed of cardboard, plastic, metal or the like having a series of circular scales imprinted thereon around the central axis 15. A pivotably mounted radially disposed arm 17 is positioned on the disc 13 and arranged to rotate around the axis 15. A radial index line 19 is marked along the center of the arm 17.

In the embodiment herein described, there are four concentric scales imprinted on the surface of the disc 13. One scale identified by the reference numeral 21 can be referred to as the main scale and serves to divide the 360° circle into 100 equal parts. A second scale positioned concentrically inside the main scale 21 and referred to as the inner scale 23 operates in effect to divide the main scale 21 by eight. Thus, the inner scale 23 and the main scale 21 represent a factor 8 table. Immediately outside the main scale 21 there is concentrically positioned an arrangement of numbers 1 to 7 periodically repeated which can be referred to as the first outer scale 25. This first outer scale 25 is preferably marked in the color black and in certain instances indicates the remainder number during the conversion process. Outside the first outer scale 25 there is concentrically positioned a second outer scale 27 which is also an arrangement of numbers 1-7 periodically repeated but is shifted in phase by four. This second outer scale 27 is preferably marked in the color red to distinguish from the first outer scale 25 and is useful to indicate the remainder number in certain of the other conversion steps.

MODE OF OPERATION

The operation of the hereinbefore device is based upon the principle that certain high digit decimal numbers are divisible by 8 and certain ones are not and this can be quickly recognized by considering the three least significant digits only as follows. If the third one from the right end is even the number is divisible by 8 if the number consisting of the two least significant digits is divisible by 8. If the number is less than three dig-

its in size, the third digit from right is zero and consequently even. If the third digit from right in the original number is odd, the number is divisible by 8 if the last two digits at the right end are divisible by 4, but not by 8. Thus . . . 856 is divisible by 8, but . . . 756 is not. But . . . 744 is divisible by 8. It does not matter how far these numbers extend to the left.

Based on this principle, the hereinbefore described device presents the remainder for a number of any digit size when divided by 8. All that has to be done to find this remainder is to set the line 19 of the arm 17 on the number on the main scale 21 that is the least significant two digit part of the number to be converted. If the third digit from the right in this number is even, the remainder is found on the first outer (black) scale 25, and if the number is odd, the remainder is found on the second outer (red) scale 27.

For example: to convert the decimal number 88,012₁₀ to its octal equivalent:

First step: set the line 19 on 12 (the two least significant digits in 88,012) on the main scale 21, find first remainder 4 which is the least significant digit of octal number on the black remainder scale 25 since the third from right digit in 88,012 is even. Subtract 4 from 88,012 to obtain 88,008, then divide by 8 which equals 11,001.

Second step: set the line 19 on 1 on the main scale 21, find remainder 1 which is the second digit from right in the octal number on the black remainder scale 25 since the third digit in 11,001 is even. Subtract 1 from 11,001 to obtain 11,000, then divide by 8 which equals 1,375.

Third step: set the line 19 on 75 on the main scale 21, find remainder 7 which is the third digit from right in the octal number on the red remainder scale 27 since the third digit in 1,375 is odd. Subtract 7 from 1,375 to obtain 1,368, then divide by 8 which equals 171.

Fourth step: set the line 19 on 71 on the main scale 21, find the remainder 3 which is the fourth digit from the right in the octal number on the red remainder scale 27 since the third digit in 171 is odd. Subtract 3 from 171 to obtain 168, then divide by 8 which equals 21.

Fifth step: In this and the next step we deal with numbers of less than three digits for which the remainders are on the black scale 25. Set the line 19 on 21 on the main scale 21, find the remainder 5 which is the fifth digit from the right in the octal number. Subtract 5 from 21 to obtain 16, then divide by 8 which equals 2.

Sixth step: Set the line 19 on 2 on the main scale 21, find the remainder 2 which is the sixth digit from the right in the octal number. Subtract 2 from 2 to obtain

0, then the procedure is at its end. The result is 88,012₁₀ equals 253,714₈.

Note that besides finding the remainders as described above, the ruler device is useful for dividing the numbers reduced by the remainder to avoid miscalculations. This is accomplished by using the inner scale 23 to obtain the quotient of the figure on the main scale 21. The multiplication process can be carried out in a similar manner by using the same scales in reverse.

10 Although the invention has been illustrated and described in terms of a preferred embodiment thereof, it will be apparent to those skilled in the art that certain changes alterations, modifications and substitutions, particularly with respect to the construction details, 15 can be made in the arrangement and location of the various scales without departing from the true spirit and scope of the appended claims. Also, it should be noted that the element 17 which is described as a pivotably mounted radially disposed arm could be replaced by a clear plastic disc rotatably mounted with a radial index line marked thereon.

20 Having thus set forth and disclosed the nature of my invention, what I claim is:
